DISPLAY RACK FOR GOLF CLUBS AND THE LIKE

Harry L. Douglas, 2991 Sunnynook Drive,
Los Angeles, Calif. 90039

Filed May 13, 1966, Ser. No. 2,283

Term of patent 14 years

(Cl. D80—10)

FIG. 1 is a perspective of a display rack illustrating my new design.

FIG. 2 is a side elevation thereof, the golf club shown in dot-dash lines being for illustrative purposes only.

FIG. 3 is a plan view thereof.

I claim:

The ornamental design for a display rack for golf clubs and the like, as shown and described.
